United States Patent Office

Des. 208,363
Patented Aug. 22, 1967

208,363

HOE

Charles F. Baker, Stratford-upon-Avon, England, assignor to George Baker Limited, Birmingham, England, a British company

Filed July 22, 1966, Ser. No. 3,180

Claims priority, application Great Britain May 12, 1966

Term of patent 14 years

(Cl. D39—1)

FIGURE 1 is a front elevation of a hoe showing my new design with portions broken away to indicate indeterminate length,

I claim:

The ornamental design for a hoe, as shown and described.
